WALTER J. COOMBS, OF QUINCY, MASSACHUSETTS, ASSIGNOR TO TUBULAR RIVET & STUD COMPANY, OF BOSTON, MASSACHUSETTS, A CORPORATION OF MASSACHUSETTS.

LACING HOOK OR STUD SETTING MACHINE.

1,141,775.

Specification of Letters Patent.

Patented June 1, 1915.

Application filed June 17, 1905. Serial No. 265,638.

To all whom it may concern:

Be it known that I, WALTER J. COOMBS, citizen of the United States, and resident of Quincy, county of Norfolk, Massachusetts, have invented certain new and useful Improvements in Lacing Hook or Stud Setting Machines, of which the following is a specification.

The present invention relates to machines for setting lacing hooks or studs upon the uppers of shoes and its primary object is to provide a machine by which the hooks or studs may be accurately and rapidly set along the edges of the two sides of the upper.

In setting this form of lacing devices upon the uppers of shoes it has heretofore been the practice to set the hooks along the edge of one side of the upper by presenting the upper to the setting devices in position to first set the hook nearest the top edge of the upper, and then spacing the work between successive setting operations to set the hooks intermediate the upper hook and the top eyelet, the hooks on the other side of the upper being set by presenting that side of the upper to the setting devices in position to first set the lower hook (which is just above the top eyelet) and then spacing the work between successive setting operations to set the hooks between this hook and the top edge of the upper. This manner of setting the hooks involves the accurate adjustment of the gages arranged on opposite sides of the setting devices and also involves the accurate positioning on the part of the operator of each side of the upper with relation to the corresponding gage.

Any carelessness or inaccuracy on the part of the operator in either setting the gages or in presenting the work to the setting devices, results in an inaccurate positioning of the lacing hooks upon the two sides of the upper so that the hooks in the finished shoe are not equally spaced from the top edge of the upper and are not in proper alinement with each other upon the shoe.

In practising my invention I set the opposing hooks on the two sides of the upper simultaneously and in accurate alinement with each other so that there is practically no danger of spoiling the work by inaccurate positioning and spacing of the opposing hooks. I accomplish this result by pro-

viding two reversely arranged setting anvils which are in axial alinement with each other and which coöperate with two opposed hook supporting plates in simultaneously setting the two opposing hooks upon the opposite sides of the upper, one side of the upper being presented between one anvil and the opposing hook supporting plate and the other side of the upper being simultaneously presented between the other anvil and the opposing hook supporting plate. I also provide mechanism for feeding the hooks into position upon the hook supporting plates with their shanks extending toward the corresponding setting anvils and with the hooks similarly positioned so that they will be properly set with relation to the edges of the two sides of the upper. In order to increase the rapidity with which the successive hooks are set and also to insure the accurate and uniform spacing of the opposing hooks along the edges of the two sides of the upper, I also prefer to employ devices for feeding forward the two sides of the upper in unison between successive setting operations.

In embodying the broader features of my invention in a simple and efficient machine which may be conveniently and successfully operated at a high rate of speed, I have employed certain features relating more or less to the specific arrangement and construction of the various mechanisms which are of importance in securing the best results, although they are not essential to a practical embodiment of the broader features. All the various features of the invention per with relation to the corresponding gage will be pointed out in the claims and will be understood from the following detailed description of the machine in which I have embodied them and which is shown in the accompanying drawings.

In these drawings, Figure 1 is a front elevation of the machine; Fig. 2 is a side elevation looking toward the right in Fig. 1; Fig. 3 is a transverse sectional elevation through the setting and feeding devices; Fig. 4 is a partial front elevation showing the hook feeding guideways and separators; Fig. 5 is a detail plan view showing the devices for feeding and clamping the work; Fig. 6 is an elevation of the clamping devices; Fig. 7 is an enlarged sectional view showing one of the hook carrying plates and

the devices for operating it; Fig. 8 is a horizontal section on line 8—8 Fig. 7; and Fig. 9 is an enlarged sectional view on line 9—9 Fig. 8.

5 In the machine shown in the drawings the setting devices embody two setting anvils A' A² formed in opposite sides of an anvil plate A and arranged in axial alignment with each other. These anvils are properly 10 shaped to spread and clench the shanks of the hooks which are forced against the anvils by two opposed hook supporting plates B' B². These hook supporting plates are shaped to enter between the head and shank 15 of the hook and are recessed at b (Fig. 7) to receive the neck of the hook and position the hook upon the plate in the usual manner. A space or pocket b' is formed below the hook supporting plate the sides of which 20 serve to retain the head of the hook in proper position and the hook is held in position upon the plate by means of a spring pressed retaining pin b² which engages the outer surface of the head.

25 The hook supporting plates are carried upon reciprocating plungers and are moved toward the hook setting anvils to force the shanks of the hooks carried thereby through the material and against the setting anvils. After 30 the setting operation has been completed and as the hook supporting plates move away from the setting anvils, the plates are disengaged from the hooks so that they do not interfere with the advance movement of the 35 material in spacing the work and so that the hooks do not interfere with the return movement of the plates. After the setting operation the plates are moved in a direction away from the setting anvil to bring them 40 into position to receive the succeeding hooks and are also returned into position to co-operate with the anvils upon their next forward movement.

45 The hook supporting plate B² is formed upon the upper end of a post b⁸ which is secured to a slide b⁴. This slide b⁴ is guided upon a block b⁵ extending from a rod b⁶ which is mounted in the upper end of the plunger b⁷. The rod b⁶ is forced upward by 50 a spring b⁸ and its upward movement is limited by a pin b⁹ which extends through a slot b¹⁰ in the rod. This pin and slot also prevents the rod from turning in the plunger and maintains the block b⁵ in proper relation 55 on the plunger.

When the plunger b⁷ is in its lower position, the slide b⁴ is in its inner position as shown in Fig. 7 and at this time the recess b in the inner side of the plate B² 60 registers with the lower end of a hook feeding guideway C². The slide b⁴ is held in this inner position by means of a spring pawl b¹¹ which engages a shoulder b¹² formed on the upper end of a pivoted block b¹³. By the engagement of the pawl b¹¹ with the block b¹³.

the slide b⁴ is held in its inner position against the tension of a spring b¹⁴ mounted in the block b⁵ and engaging a pin b¹⁵ which projects downward from the slide through a slot b¹⁶ formed in the block. While the plate B² is in this position at the end of the guideway C² a hook is transferred from the guideway on to the plate as indicated in dotted lines in Fig. 7, the retaining pin b² yielding against the tension of the spring b¹⁷ as the head of the hook passes forward over the end of the retaining pin. After the hook has been thus fed on to the plate, the plunger b⁷ is forced up against the tension of the spring b¹⁸ carrying the hook upward and forcing the shank of the hook through the material and against the setting anvil A². As the hook is forced against the anvil, the spring b⁸ yields until the block b⁵ engages the end of the plunger b⁷ when the setting operation 85 is completed. As the end of the plunger b⁷ is thus forced against the block b⁵ it acts against the end of a pin b¹⁹ which underlies the end of the pawl b¹¹ and lifts the pin and pawl. This movement of the pin b¹⁹ and pawl b¹¹ disengages the pawl from the pivoted block b¹³ which block is immediately swung forward under the pawl by the action of the spring pressed pin b²⁰ so that any accidental reengagement of the pawl b¹¹ with the shoulder b¹² is prevented. During the setting operation the slide b⁴ and plate B² are held from outward movement by reason of the pressure exerted on the hook by the plate and setting anvil. As soon as the plunger b⁷ and plate B² start downward, this pressure is relieved and the slide b⁴ and attached plate B² are immediately retracted by the action of the spring b¹⁴, thus disengaging the plate B² from the hook. The pin b¹⁹ immediately drops down to the position shown in Fig. 9. During the downward movement of the plunger b⁷ the slide b⁴ and plate B² are returned to the position indicated in Fig. 7 by means of a lever b²¹, the upper end of 110 which engages a slot in the slide b⁴ and the outer end of which is arranged to engage an abutment roll b²² secured to the frame of the machine. When the slide b⁴ is thus returned, the pawl b¹¹ reengages the block b¹³ and retains the slide and plate B² carried thereby in position until the next setting operation, the action of the spring b¹⁴ drawing the block b¹³ into the position shown in Fig. 9 as soon as the lever b²¹ disengages the roll b²². 115

120 The guideway C² through which the hooks are fed to the hook supporting plate B², curves downward from the lower end of a hook chute c and individual hooks are separated from the series of hooks in the hook chute and directed down the guideway by means of a separator c'. This separator is pivoted at c² and is provided with an arm c³ which normally stands in the position shown in Fig. 8 across the end of the supporting 125 130

5 rail c^4 of the hook chute and prevents the entrance of the lower hook into the guideway C^2 . The separator is also provided with a finger c^5 arranged below the arm c^8 and separated therefrom by a space sufficient for the passage of the necks and heads of the hooks.

10 By swinging the separator about its pivot the finger c^5 may be brought into position to register with and form a continuation of the supporting rail c^4 of the hook chute and when the separator is moved into this position the lower hook in the chute moves forward and rests with its neck upon the finger c^5 . When in this position the neck of the hook is in line with the guiding slot c^6 of the guideway C^2 which is of sufficient width to allow the passage of the neck of the hook but not of sufficient width to allow the passage of either the head of the hook or the base of the shank. When the separator is returned to the position indicated in Fig. 3 the finger c^5 disengages the neck of the hook allowing the hook to slide down the guideway C^2 , the arm c^8 moving down into position to prevent the entrance of the succeeding hooks into the guideway. The hook thus separated from the series of hooks in the hook chute is arrested and retained at the lower end of the guideway C^2 by means of a spring finger c^{80} which extends into the path of the hook. The hook remains in this position at the end of the guideway until the hook supporting plate B^2 has been re-
35 turned into the position indicated in Fig. 7 when the hook is fed forward out of the guideway and into position on the plate by means of a feeding slide c^7 mounted in guideways below and back of the rails of the guideway C^2 . The movements of the separator are controlled from this feeding slide by means of a pin c^8 carried by the slide and arranged to engage a cam surface c^9 on the separator. The cam surface is held
40 yieldingly in engagement with the pin c^8 by means of a spring c^{10} .

When the feeding slide c^7 advances to transfer the hook from the end of the guideway on to the hook supporting plate the pin c^8 so 50 rides from under the cam surface c^9 so that the separator is swung into position to bring the finger c^5 in line with the supporting rail of the hook chute. When the feeding slide is retracted the pin c^8 acts against the cam surface c^9 to rock the separator into the position shown in Fig. 3, thus delivering a hook into the guideway preparatory to the next forward movement of the feeding slide.

55 The construction and mode of operation of the hook supporting plate B' is similar to the construction and mode of operation already described in connection with the hook supporting plate B^2 . The individual hooks are fed to the hook supporting plate

60 B' through a guideway C' similar to the guideway C^2 and the devices for separating and feeding individual hooks are similar in construction and mode of operation to the devices for separating and feeding the hooks to the plate B^2 . The hooks which are to be fed to the plate B' are however, arranged in reverse position upon the supporting rail c^{40} of the hook chute so that the hooks are fed through the guideway C' with the shanks extending below the rails of the guideway instead of with the shanks extending above the rails of the guideway as in the case of the hooks delivered to the guideway C^2 . By these separating and feeding devices therefore, the hooks are fed to the hook supporting plates with their shanks extending in reverse direction but with the opening between the head and the shank of the hook similarly arranged. By the simultaneous operation of the plungers carrying the hook supporting plates, opposing hooks may be simultaneously set upon the two sides of the upper with the necks of the hooks adjacent to the edges of the two sides of the upper.

65 The hooks are supplied to the supporting rails c^4 and c^{40} of the hook chutes from hoppers D^1 D^2 by separating devices of any suitable construction, the supporting rails being led from the hoppers in such manner that the hooks upon the supporting rails of the two hook chutes will be presented to the guideways C' C^2 in reverse positions.

70 The plunger b^7 which carries the hook supporting plate B^2 is forced upward by means of a cam b^{23} secured to the main cam shaft E of the machine and arranged to act upon one end of a lever b^{24} the opposite end of which engages the lower end of the plunger b^7 . The plunger is retracted under the control of the cam b^{23} by means of the spring b^{18} shown in Fig. 7. The plunger b^{70} which carries the hook supporting plate B' is operated in unison with the plunger carrying the hook supporting plate B^2 by means of an eccentric b^{25} . The eccentric is engaged by an eccentric strap b^{26} which is connected by a rod b^{27} with one end of a lever b^{20} , the other end of which is connected with the plunger b^{70} . The eccentric strap b^{26} and the rod b^{27} are yieldingly connected together by means of a spring b^{80} so that the connections between the eccentric and the plunger b^{70} may yield to prevent injury to the parts in case a hook should become misplaced and remain in position to prevent the return of the parts carried by the plunger to position with the plate B' in register with the end of the guideway C' .

75 The feeding slides c^7 c^{70} are actuated in unison by means of a cam c^{11} secured to the cam shaft E and arranged to engage one end of a lever c^{12} . The lever is held in engagement with the cam by a spring c^{13} and is connected with the feeding slide c^7 by means

of a roller c^{14} carried by the slide and arranged to engage a slot c^{15} in the lever. The upper end of the lever is provided with a roll c^{16} which engages a slot c^{17} formed in the end of a second lever c^{19} . The lever c^{19} is connected with the slide c^{70} by means of a roll c^{20} arranged to engage a slot c^{21} in the lever. The levers and the connections with the slides are so arranged and proportioned that the slides will be reciprocated in unison as the cam shaft E revolves, by the action of the cam c^{11} upon the end of the lever c^{12} .

The two sides of the upper or two pieces or edges of the material in which the hooks are to be set, are positioned by the operator on opposite sides of the anvil plate A and are held in position by two spring operated clamping plates F' F^2 . To assist the operator in positioning the work on opposite sides of the plate and also to assist in uniformly guiding the two pieces of work, rear guides G' G^2 are adjustably secured upon the anvil plate in position to be engaged by the edges of the work. The clamping plate F' is secured to the front end of an arm f' , while the clamping plate F^2 is secured to a similar arm f^2 . The arms f' f^2 are secured to two vertical rods f^3 f^4 and each arm is provided with a hole through which the rod carrying the other arm extends, as indicated in Fig. 6. The arms are connected by a spring f^6 which tends to hold the clamping plates F' F^2 in engagement with the opposite sides of the anvil plate. The rods f^3 f^4 are also connected by means of a lever f^8 pivoted at f^7 and provided on opposite sides of the pivot with slots engaging pins which project from the rods so that the movement of either rod will be accompanied by a movement of the other rod in the opposite direction. When the material is to be inserted between the clamping plates and the anvil, the clamping plates are moved away from the anvil plate by drawing downward the rod f^4 which carries the plate F^2 . This downward movement of the rod f^4 may be produced by a treadle or other suitable device connected by means of a cord f^8 with the lower end of the rod f^4 . When the rod f^4 is thus depressed the rod f^3 is simultaneously lifted by the action of the lever f^6 and thus both the clamping plates are simultaneously moved away from the anvil plate so that the material may be readily introduced between the clamping plates and anvil. When the lever f^6 is released the clamping plates will immediately be engaged with the material on opposite sides of the anvil plate and hold it firmly in position during the setting operation. After each setting operation, the clamping plates should be withdrawn from engagement with the work in order to allow the work to be spaced preparatory to the next

setting operation. This is automatically performed by means of a cam f^9 secured to the cam shaft E and acting upon one end of a lever f^{10} the opposite end of which engages a roll f^{11} mounted on the rod f' . The clamping plates F' F^2 are cut away in line with the setting anvils as indicated in Fig. 5, to allow the passage of the hook supporting plates as they force the hooks through the material and against the setting anvils. The plates are also cut away to accommodate the movements of the feeding devices which will be referred to later on in the description of the machine.

If the spacing of the work is to be manually performed the operator will simultaneously insert the two sides of the upper between the clamping plates and the opposite sides of the anvil plate, being careful to have the top and inner edges of the two sides of the upper in register with each other, and will position the sides of the upper in proper relation to the hook setting anvils. The machine will then be started in the manner usual to hook setting machines, and by the operation of the hook setting devices the two hooks which are to be opposed to each other upon the finished shoe, will be simultaneously set upon the two sides of the upper and in accurate alignment with each other. After each setting operation the operator will simultaneously and uniformly advance the two sides of the upper to space the work for the next setting operation. By this setting operation the second two opposing hooks will be set in accurate alignment with each other, and so on until the requisite number of hooks have been set, when the operation of the machine will be arrested. Any variation in the initial positioning of successive pieces of work or any variation in the spacing between successive setting operations, will not affect the alignment of the hooks in the finished shoe, since the opposing hooks are simultaneously set in accurate alignment.

In order to provide for the rapid setting of the hooks along the edges of the material in which the hooks are being set, and also to insure the accurate spacing of the work between successive setting operations, I prefer to provide the machine with mechanism for feeding the work between the setting devices. In the construction of feeding mechanism which I prefer to employ for this purpose the two sides of the upper, or other pieces of work, are simultaneously operated upon by two feeding punches H' H^2 which operate to punch holes in the work for the reception of the shanks of the hooks and to bring these holes into register with the setting anvils. The feeding punches are secured on two levers h' h^2 pivoted on a shaft h^3 and projecting upon opposite sides of the anvil plate A. The levers h' h^2 are

rocked upon the pivot h^8 to move them toward and away from the opposite sides of the anvil plate by means of two oppositely arranged cams h^5 h^6 secured to a cam shaft 5 I and working in recesses h^7 h^8 formed in the rear ends of the levers. The cams h^5 h^6 are so arranged upon the cam shaft that the levers h^1 h^2 and the punches carried thereby will move simultaneously toward and away 10 from the opposite sides of the anvil plate A. In the operation of punching and feeding the work the levers h^1 h^2 are moved toward the anvil plate to enter and pierce the work held on opposite sides of the plate, are then 15 advanced toward the right in Fig. 1 until the punches register with the anvils on the plate, are then moved away from the plate to disengage the punches from the work, and are then retracted to the initial position 20 shown in Figs. 1 and 5. In order that the feeding and return movements may be imparted to the punch carrying levers, the pivoted shaft h^3 on which the levers are mounted, is carried in a slide h^9 mounted in suitable guides arranged parallel to the cam shaft I. The forward and return movements 25 are imparted to this slide h^9 by means of a cam h^{10} secured to the cam shaft E and engaging one end of a lever h^{11} , the other end of which is connected to the slide h^9 . In order that the feeding movements of the feeding punches may be varied to correspond to any desired spacing of the hooks, the connection between the slide h^9 and lever 30 h^{11} is so constructed that the motion imparted to the slide by the lever may be varied. This connection consists of an arm h^{12} pivoted to the slide h^9 and adjustably secured in position by means of a bolt h^{13} passing 35 through a slot h^{14} which is concentric with the pivot of the arm. This adjustable arm h^{13} is provided with a pin h^{15} arranged to engage a segmental slot h^{16} formed in the lever h^{11} . The slot h^{16} is so formed and arranged that 40 when the punches H' H^2 are in register with the setting anvils the slot is concentric with the pivot of the arm h^{12} . Any adjustment of the arm about its pivot will not therefore affect the extreme forward position of the 45 feeding punches which will in every case be in register with the setting anvils. By adjusting the arm h^{12} about its pivot on the slide h^9 however, the extent to which the punches will be retracted by the movement 50 of the lever h^{11} may be varied and thus the spacing effected by the feeding punches be changed as desired. The lever h^{11} may be provided with a scale if desired showing the adjustment of the arm h^{12} corresponding 55 to the spacing required for any given style or size of shoe or such scale may be formed on the arm h^{12} adjacent to the slot h^{14} .

The cam shaft I is moved longitudinally 60 in unison with the movements of the feed-

ing slide h^9 by the engagement of the levers h^1 h^2 with the opposite sides of a disk I' secured to the shaft and interposed between the levers and between the cams h^5 h^6 .

The cam shaft E which is the main shaft 70 of the machine is driven from a pulley E' adapted to be connected with and disconnected from the shaft by means of an ordinary stop clutch motion which is thrown into and out of operation in the common 75 and well known manner by means of a pin E² which may be operated through a treadle in the usual manner. The cam shaft I is driven in unison with the cam shaft E through the gears E³ I² and the intermediate gear I³. The gear I² is splined upon the shaft I and is held from lateral movement as the shaft I slides backward and forward 80 through the gear by means of a strap I⁴ shown in Fig. 1.

The hoppers D' D² are driven from the shaft E through a belt J which drives a shaft J' connected with the hoppers by worms J² and worm wheels J³ which are secured to the hopper shaft as indicated in 90 Fig. 2.

In operating the machine the operator inserts the two uppers on opposite sides of the anvil plate with the top edges of the uppers the distance in advance of the punches corresponding to the desired space between the tops of the uppers and the first hook and then starts the machine. As the cam shafts revolve the punches approach 95 each other and are forced through the work upon opposite sides of the anvil plate and then advanced until they are in register with the setting anvils. During this movement of the feeding punches, the plungers carrying the supporting plates B' B² have 100 been retracted and the slides carrying the supporting plates forced forward bringing the supporting plates into register with the ends of the feed guideways C' C². The feeding slides have also moved forward transferring the hooks from the guideways to the supporting plates. As the cam shafts continue to revolve the feeding punches are moved away from each other to disengage 105 the work and are immediately retracted toward their initial positions. During this movement of the feeding punches the plungers carrying the supporting plates advance and as the feeding punches reach their initial positions the setting operation is completed 110 and the plungers carrying the supporting plates partially retracted into the positions indicated in Figs. 1, 2 and 3. During the feeding operation the clamping plates F' F² are withdrawn to allow the feeding forward of the work and are immediately reengaged with the work as soon as the advance movement of the feeding punches is completed and continue to hold the work in 115 position during the setting operation and 120 125 130

until the feeding punches have again been forced into the work. During the feeding action of the punches the operator manipulates or controls the work so that the edges 5 of the uppers remain uniformly in engagement with the guides G' G². The setting and feeding operations will be repeated in rapid succession as long as the pin E² is retracted and upon the release of the pin the 10 parts will complete the cycle of operations and come to rest in the position indicated in Figs. 1, 2 and 3, in which the setting operation has been completed and the feeding and punching devices returned to initial position 15 preparatory to punching the holes for the reception of the shanks of the hooks which are to be set at the next setting operation.

What I claim and desire to secure by Letters Patent is:

1. A machine for setting lacing hooks or studs having in combination two opposed sets of hook setting devices fixed in the direction of feed, and mechanism for feeding hooks to each set of hook setting devices.

2. A machine for setting lacing hooks or studs having in combination an anvil plate provided with a hook setting anvil on each side arranged one in line with the other, two 30 opposed hook supporting plates, mechanism for feeding hooks onto said plates, mechanism for reciprocating said plates, and mechanism for disengaging said plates from the hooks after the setting operation.

3. A machine for setting lacing hooks or studs having in combination, two reversely arranged setting anvils in line with each other, two opposed hook supporting plates coöperating therewith, mechanism for feeding 40 hooks onto said plates, two opposed feeding punches, and mechanism operating said punches in unison to engage the work, advance into register with the anvils, disengage the work and return to initial position.

4. A machine for setting lacing hooks or studs, having in combination two fixed reversely arranged setting anvils in line with each other, two opposed hook supporting plates, guideways through which hooks are 50 fed to the plates, mechanism for reciprocating the plates between the ends of the guideways and the anvils, mechanism for disengaging the plates from the hooks, mechanism for transferring hooks from the guideways to the plates, and mechanism for feeding hooks to the guideways with their shanks in reverse positions.

5. A machine for setting lacing hooks or studs having in combination, an anvil plate 60 provided with a hook setting anvil on each side arranged one in line with the other, two coöperating hook supporting plates mounted in fixed relation to the anvils in the direction of the feed mechanism for feeding hooks onto said plates, clamping

plates for holding the work against opposite sides of the anvil plate, and mechanism for withdrawing said clamping plates.

6. The combination with two opposed sets of setting devices, of two opposed feeding punches, levers carrying said punches, a feed slide on which said levers are pivoted, mechanism for simultaneously moving said levers in opposite directions, and mechanism for reciprocating the feed slide.

7. The combination with two opposed sets of setting devices, of two opposed feeding punches, levers carrying said punches, a feed slide on which said levers are pivoted, oppositely acting cams for operating said levers, and mechanism for reciprocating the feed slide to bring the punches into register with the setting devices and return them to initial position.

8. The combination with two opposed sets of setting devices, of two opposed feeding punches, levers carrying said punches, a feed slide on which said levers are pivoted, oppositely acting cams for operating said levers, mechanism for reciprocating the feed slide 90 to bring the punches into register with the setting devices and return them to initial position, and means for varying the initial position of the punches.

9. The combination of two opposed feeding punches, levers carrying said punches, a feed slide on which said levers are pivoted, a cam shaft parallel to the movement of said slide, oppositely acting cams on said shaft for operating said levers, mechanism for reciprocating the feed slide, and devices for maintaining the operative connection between the cams and levers.

10. The combination of two opposed feeding punches, levers carrying said punches, a feed slide on which the levers are pivoted, mechanism for operating the levers to engage and disengage the punches with the work, an arm adjustably pivoted to the slide, a lever for reciprocating the slide provided with a slot concentric with the pivot of the arm when the slide is in its advanced position, and a pin on the arm engaging the slide.

11. A machine for setting lacing hooks or studs having in combination, a fixed anvil plate provided with a hook setting anvil on each side arranged one in line with the other, two opposed plungers mounted to reciprocate in fixed relation to the anvil plate, hook supporting plates on the plungers coöperating with the setting anvils, clamping plates for holding the work against opposite sides of the anvil plate,

feeding devices for engaging the work, mechanism for simultaneously operating the feeding devices to engage the work, feed it forward, and to then disengage the work and return to initial position, and mechanism for withdrawing the clamping plates.

during the feeding movement of the feeding devices.

12. A machine for setting lacing hooks or studs having in combination an anvil plate 5 provided with a hook setting anvil on each side arranged one in line with the other, two hook supporting plates coöperating therewith, mechanism for feeding hooks onto said plates, clamping plates, two feeding 10 punches, mechanism for operating said punches in unison to engage the work, advance into register with the anvils, disengage the work, and return to initial position, and mechanism for withdrawing the 15 clamps during the advance of the punches.

13. The combination of two opposed sets of setting devices, two opposed feeding punches, and mechanism for operating said punches in unison to engage the work, advance into register with the setting devices, disengage the work and return to initial 20 position.

14. A machine for setting lacing hooks or studs, having, in combination, a fixed anvil 25 plate provided with a hook setting anvil on each side arranged one in line with the other, two opposed hook supporting plates coöperating therewith, two opposed feeding devices, and mechanism for operating said 30 devices in unison to engage the work, advance into register with the setting devices, disengage the work, and return to initial position.

15. A machine for setting lacing hooks or studs having in combination, two reversely 35 mounted sets of hook setting devices arranged in line with each other and in fixed relation in the direction of the feed, mechanism for feeding hooks to the two sets of setting devices, and mechanism for feeding 40 the work in unison to the two sets of setting devices.

16. The combination with two opposed sets of setting devices fixed in the direction of feed, of two opposed feeding devices, and mechanism for operating said feeding devices in unison to engage the work, advance 45 into register with the setting devices, disengage the work, and return to initial position. 50

17. A machine for setting lacing hooks or studs having in combination, two reversely mounted sets of hook setting devices arranged in permanent alinement with each other in the direction of feed, mechanism 55 for feeding lacing hooks to the two sets of setting devices, and mechanism for feeding the two sides of an upper to the two sets of setting devices and maintaining the sides of the upper in fixed relation to each other. 60

In witness whereof, I have hereunto set my hand, this 13th day of June 1905.

WALTER J. COOMBS.
In the presence of—
IRA L. FISH,
KATHARINE A. DUGAN.
